FABRIC CONTACTING CIRCUIT CLOSER
FOR KNITTING MACHINES

Michael Wachsman, Brooklyn, N. Y.

Application August 10, 1946, Serial No. 689,735

1 Claim. (Cl. 66—166)

1

The object of this invention is to provide a novel and improved fabric contacting circuit closer for knitting machines for closing an electric stop circuit to actuate a knitting machine stopping device when a tear, run, a dropped stitch or other irregular or abnormal condition appears or occurs in the knitted fabric.

In the operation of knitting machines which include electric circuit closing devices it is of the utmost importance that such devices be most carefully protected against deposits and accumulations of dirt, paraffin, fluff from the fabrics and yarns which unavoidably result from the operation of the machines and hinder or even prevent the efficient operation of the electric circuit to stop the machine promptly in cases of trouble. It is a prime object of this invention to provide electric circuit closers in which the contacting terminals are adequately enclosed and protected. The invention is embodied in fabric contacting circuit closers as hereinafter described and as illustrated in the accompanying drawings in which

Fig. 1 is a view of a circuit closer enclosed in a protecting box, the cover of the box being removed.

Fig. 2 is a sectional view of Fig. 1 taken on the line 2—2 thereof with details omitted.

Fig. 3 is a view similar to Fig. 1 but shows a circuit closer having two fabric contacting detectors.

Fig. 4 shows a circuit closer having a single fabric contacting detector with the circuit closing mechanism enclosed in a special inner protective casing.

Fig. 5 illustrates a modification of the circuit closer shown in Fig. 4.

Fig. 6 shows a circuit closer adapted for high voltage operation to avoid the use of batteries and transformers.

Fig. 7 is a diagrammatic view of circuit closing device in which fabric contacting detectors are used on both sides of the fabric.

Fig. 8 is an enlarged view of parts of the device shown in Fig. 7.

Fig. 9 is a sectional view of the detector rings shown in Fig. 7.

Fig. 10 is a view of a circuit closer embodying the invention and arranged for mechanical operation of the shipping lever of the knitting machine stop mechanism.

Fabric contacting circuit closers employing detectors in frictional contact with the fabric are shown in my Patent No. 2,168,755, dated August 8, 1939, to which reference is made for the gen-

2

eral disclosure and operation of such devices. A knitting machine is provided with a mechanism for shifting the belt or clutch whereby to stop the machine when troubles occur. Such mechanism is actuated by an electric circuit which is normally open. Certain elements in contact with the fabric are employed to close the stop circuit when abnormal conditions occur in the fabric and such abnormalities are detected by such elements. This, in brief, is the underlying principle of operation of knitting machine stop motions whether they be yarn detectors or fabric contacting detectors.

Referring to the drawings the fabric is represented at 10. In Fig. 1, a detector 12 is slidably mounted in a box 14. The detector carries an insulated contact 15 which is connected by a spring 16 to an adjustable spring support 17 in threaded engagement with a screw shaft 18 operable from outside the box by a hand knob 19 to adjust the tension of the spring. A fixed contact 20 is adjustably mounted in the box. The contact is movable in a slot 21 and secured by a nut 22 in adjusted position. The contact 20 is completely insulated by insulating members 24 which also serve to close the slot 21 to prevent the entrance of dirt.

The box may have an attaching lug 25 for mounting the device in a suitable position on the knitting machine. The detector 12 is preferably a thin flat member having a bent contact head 26. The contact 20 is connected via a battery to an electromagnet 28 which, when energized, operates the shipping lever 30, or clutch lever as the case may be, of the usual stop mechanism, not shown. The operation is well known in the art. The other side of the circuit is grounded on the machine.

The detector 12 is held in normal frictional contact with the fabric by the spring 16. When a fault occurs in the fabric the spring operates the detector to move the contact 15 into engagement with the contact 20 to close the circuit to energize the magnet and the knitting machine stops.

Fig. 3 illustrates a device in which two detectors are mounted in the box 14. In addition to the mechanism shown in Fig. 1, the device in Fig. 3 includes a detector 32 which is relatively long and extends upward into contact with the fabric. Thus a double protection is provided and a greater area of fabric is under control, the detector 32 being offset with respect to the detector 12 as shown. The detector 32 is mounted on a shaft 33 under the control of a spring 34 attached to a spring support 35 adjustably carried by a screw shaft 36. The shaft 33 also carries a contact 37

adapted to engage a fixed contact 38 which is similar to the contact 28. The operation by either or both detectors 12 and 32 serves to close the electric circuit to stop the machine.

In Fig. 4 the detecting mechanism includes contact members which are completely enclosed within a separate protective casing. In this illustration the detector 40 is of circular form ending in a pointed detector head 41. To the detector is secured a toothed contact member 42 in the form of a ring and the detector is urged into contact with the fabric by a spring 43. The contact 42 is grounded on the machine and is adapted to engage a second similar fixed contact 44. The latter is wholly insulated by suitable insulation as at 45, 45. The contact 44 is adjustable with respect to the contact 42 by means of a spring 47 and threaded nut 48, the spring acting between the casing 46 and the contact 44. The nut 48 carries a terminal 49 for the electric connection to the stop circuit. The entire unit is placed within a box 50 for attachment to the knitting machine. The casing 46 serves the double purpose of protecting the contacting elements against dirt and also in preventing ill advised attempts to repair and tamper with the mechanism by unskilled labor. The casing is preferably made of thin metal and the end 52 is soldered to the casing after the other parts have been placed within the same.

In the modification illustrated in Fig. 5 the one ring formed contact member 55 is in the form of a cup having an annular wall 56 adapted to enter a circular groove 57 in the other contact element 58. The toothed contact elements in Fig. 4 as well as the elements 55 and 58 in Fig. 5 afford unusual good contact for closing the circuit.

In Fig. 6 the electric current supply is direct from the line wires 60 to the magnet 61 and to two insulated terminals 62 and 63. The detector 96 may have any suitable form. It carries a negative and a positive contact disk 64 and 65, respectively. The disks are insulated as shown at 66 and 67. The detector with the contact disks 64 and 65 is held in frictional contact with the fabric 10 by a spring 68. The circuit is closed by a contact bridging fixed contact member 69 which is adjustable by a spring 70 and threaded nut 71 as shown. The contact 69 is wholly insulated by insulation as at 72, 73. The contact members 64 and 65 have contacting flanges 74 and 75, respectively.

When a fault occurs in the fabric the spring 68 operates the detector to the right in the drawing. The two flanges 74 and 75 contact with the two terminals 62 and 63, the current passing to the two contacting disks 64 and 65. The latter are bridged and the circuit closed by the disks contacting the fixed element 69 as will be understood. The entire circuit closing unit is enclosed within a dustproof casing 78 and no electric current passes through the knitting machine. Batteries and transformers are therefore not required.

In Fig. 7 fabric contacting detectors are used

on both sides of the fabric. To the usual dial shaft 80 of the knitting machine there is secured an inner contact ring 81 and to the needle cylinder frame, indicated at 82, there is secured an outer contact ring 83. Each ring, Fig. 7, forms an annular chamber 84, Fig. 9, in which there are mounted as many detectors 85 as may be required. Each detector carries a contact 86 and is controlled by a spring 87. Within each circular chamber 84 there is mounted an insulated contact ring 88 to which current is supplied as shown. The detectors are placed in staggered relation as shown in Fig. 8.

When a fault occurs in the fabric, one or more of the detectors 85 are operated by their respective springs 87 to close the circuit by engagement of the contacts 86 with the electric ring 88. Obviously, a greater area of fabric may be brought under control by the closely placed detectors 85.

In Fig. 10, the detector 93 within the box 91 is connected by a chain, wire or link 94 to the shipping lever 30 so that when the detector is operated as described above in connection with Fig. 1 not only will the circuit be closed to actuate the shipping lever, but the latter will be mechanically operated. This feature is provided for double protection in operation.

The circuit closers disclosed herein may be used with stationary or rotary knitting machines in any combination desired. The enclosing of the contacting elements insures freedom from dirt and insures efficient operation.

I claim:

35 A fabric contacting circuit closer for knitting machines comprising a box, a detector slidably supported in the box, a spring in said box secured to said detector for holding the same in normal frictional contact with the fabric, a normally open electric stop circuit for the knitting machine, a fixed contact in said circuit supported in the said box, a contact member carried by said detector and adapted to engage the said fixed contact to close the said circuit 40 when an abnormal condition in the fabric causes a termination of the said normal frictional contact between the detector and the fabric and means in the said box for regulating the tension of the said spring, said means comprising a 45 spring tension regulating member secured to said spring, a shaft in threaded engagement with said member to actuate the same and a knob on said shaft for operating the latter from outside the said box.

55 MICHAEL WACHSMAN.
